UNITED STATES PATENT OFFICE.

EDWARD L. WILLIAMS, OF LAKEWOOD, OHIO, ASSIGNOR TO THE WALTER A. GOLD-SMITH COMPANY, OF CLEVELAND, OHIO, A CORPORATION OF OHIO.

GARMENT YOKE.

Application filed October 9, 1924. Serial No. 742,537.

As has been indicated, this invention relates to an improved garment yoke. More particularly it comprises a yoke especially adapted for a costume slip, embodying with 5 the marginal portions positioned beneath the arm of the wearer a concealed band of elastic which is adapted to contract the adjacent material into a closely Shirred effect and serves to draw the remainder of the upper 10 edge of the yoke taut across the body of the wearer of the garment so as to provide a smooth ungathered edge at such intermediate places at the front and back of the wearer. It further contemplates the provision 15 of a garment of this type having shoulder straps which may be worn in place with morning or street dress and which may be disposed below the upper edge of said costume slip when it is worn with low-cut 20 gowns for more formal wear.

In many of the costume slips worn by women with modern types of costumes, some difficulty has been experienced in having the upper edge fit smoothly to the figure of the 25 wearer at all times. It has been the usual practice to have a draw-string concealed within a hem at the upper edge of the garment and when this is adjusted to the right tension about the body of the wearer the 30 gathers formed in the upper portion of the garment are distributed so as to prevent an accumulation of material at any one point. It has been found, however, that such initial distribution of the material cannot be maintained for any considerable time, and the 35 result is that such gathers tend to move to one side or the other and usually form a bulge which distorts the shape of the outer garment and at the same time is uncomfortable 40 for the wearer.

The principal object of the present invention is to provide a garment of the type referred to which will be free of the objectionable features just described and which 45 may be worn with a high degree of comfort and a feeling of security in so far as the effect of such under garment upon the smooth set of the outer garment is concerned. A further object of the invention is to provide 50 a garment of the type described which may be satisfactorily used for both day and evening wear, inasmuch as it permits the disposal of the usual straps, which normally extend over the shoulders, within the upper 55 edge of the garment and provides a suffi-

ciently elastic upper edge to satisfactorily hold the garment in place upon the body of the wearer independently of said shoulder straps. To the accomplishment of the foregoing and related ends, the said invention, 60 then, consists of the means hereinafter fully described and particularly pointed out in the claims.

The annexed drawing and the following description set forth in detail one method 65 and one product exemplifying my invention, such disclosed procedure and product constituting, however, but one of various applications of the principle of my invention.

In said annexed drawing:

Fig. 1 is a plan view showing the front section of a garment embodying my invention; Fig. 2 is a plan view of a back section adapted to form a complete garment with the section shown in Fig. 1; Fig. 3 is a partial front elevation showing the completed garment; Fig. 4 is a detail sectional view of the Shirred portion of the garment taken along the line 4-4 shown in Fig. 3, looking in the direction of the arrows; Fig. 5 80 is a detail sectional view taken along the line 5-5 shown in Fig. 3; Fig. 6 is an enlarged detail view showing the Shirred portion of the upper edge of the garment; and Fig. 7 is a diagrammatic view showing one 85 of the side pleats of the garment.

The garment comprises two sections, a front section 1 and a back section 2. The lower portion 3 of the front section is of larger area than the upper portion 4 thereof, 90 both in width and length. As shown in Fig. 1, the lower and upper sections are of rectangular outline but the upper section is of approximately two-thirds the width and height of the lower section. At the meeting 95 line of the upper and lower sections a transverse cut 5 is extended inwardly from either side a distance approximately equal to the extension of said lower section beyond the side edge of the upper section. This cut 100 permits the outer edge 6 of the lower section to be sewed to the adjacent edge 7 of the back section of the garment, in alignment with the adjacent side edge 8 of the upper portion of the front section. The 105 fullness of the garment is ordinarily taken up with one or more pleats 9 and this construction provides for adequate fullness of the garment at the hips of the wearer.

Across the upper edge of the front section 110

of the garment a hem is formed and adjacent each side edge thereof a strip of elastic is enclosed within said hem. In order to facilitate the sewing of the elastic into the side portions of the upper edge it has been found desirable to provide a score or cut 13 in the material at points spaced from each of the side edges, said scores extending a short distance into the body of the garment, 10 in order that the sewing of the elastic may be quickly and accurately accomplished without encroaching upon the central space of the garment. The insertion of the elastic in the marginal portions of the upper 15 edge of the front section is preferably completed before the central portion of the hem is made. Said hem thus is formed in three sections across the upper edge of the front section of the garment instead of formed in a single operation as in the making of a garment wherein a draw-string is to be inserted at the upper edge. After the completion of the hem 11 across the central portion of the front section of the garment and the 20 forming of a hem 14 across the top edge of the back section of the garment, the front and back portions of the garment are brought together and their side edges are stitched together in the usual manner. At 25 a point adjacent the inner ends of the inserted elastic one end of a shoulder strap 15 is secured, the opposite end being preferably connected with the back section of the garment at a point spaced a suitable distance 30 from the side seam thereof.

The cuts or scores 13 formed across the upper portion of the front section are stitched together as soon as the elastic has been inserted within the respective side 40 hem. This operation serves to slightly reduce the fullness of the material at the points where said seams are located.

The elastic is preferably sewed into the garment while the hem is being formed. 45 This operation is most rapidly carried out by means of a machine forming a plurality of rows of stitches. As illustrated in Fig. 3, three rows of stitches are disclosed, the two upper rows 16, 17, passing through the 50 elastic and the lower row 18 forming the bottom margin of the hem and being spaced below the lower edge of the elastic. The elastic is sewed into the hem with the cloth pulled smooth and the elastic strip under 55 tension and as soon as the hem is completed the tension on the elastic is released and the upper edge of the garment enclosing the elastic is drawn into a series of evenly spaced gathers 19 (as is shown in Fig. 6). The 60 size of the gathers formed is controlled by the size of the individual stitches which pass through the material of the folded upper edge and the tension upon the elastic when they are being formed. The upper edge at 65 the points where the elastic has been in-

serted will present a closely Shirred effect which will not be a discomfort to the wearer of the garment. Thus there has been provided a garment having a smooth form fitting upper edge wholly free from objectionable gathers across the front and back and thus provides for the perfect fit and smoothness of appearance of the outer garments.

Other forms may be employed embodying the features of my invention instead of the one here explained, change being made in the form or construction provided the elements stated by any of the following claims or the equivalent of such stated elements be employed, whether produced by my preferred method or by others embodying steps equivalent to those stated in the following claims.

I therefore particularly point out and distinctly claim as my invention:—

1. A yoke for a garment having a front and back section with the side edges stitched together, a hem formed entirely across the upper edge of the back section, a hem section enclosing an elastic strip formed into gathers at the top edge of the front section adjacent each side thereof terminating at downwardly extending scores provided to permit insertion of said strips and then stitched to remove fullness in the upper portion of said garment, and a smooth, straight hem of even depth therewith interposed between said gathered sections of hem.

2. A costume slip having a front section formed of a lower portion of larger area and an upper portion of smaller area each of substantially rectangular outline and having transverse cuts extending inwardly from either side at the meeting point of said portions a distance approximately equal to the extension of the lower portion beyond the side edge of the upper portion, and said slip having a back section of substantially rectangular outline, said front and back sections of the slip having their side edges stitched together in true alignment, the fullness of the lower portion of the front section being taken up with a plurality of pleats, a hem formed entirely across the upper edge of the back section, a hem section enclosing an elastic strip formed into gathers at the top edge of the front section adjacent each side thereof terminating at downwardly extending scores provided to permit the insertion of said strips and then stitched to remove the fullness in the upper portion of said garment, and a smooth straight hem of even depth therewith interposed between said gathered hem sections.

3. The method of making a yoke for a garment having a front and back section which comprises forming a hem at the upper edge of the back section, providing a pair of scores extending downwardly from the upper edge of the front section parallel

to the side edges and in spaced relation thereto, forming hems adjacent each of said side edges by turning the material thereof downwardly over a strip of elastic material, sewing said elastic material under tension into said turned-over material, forming a smooth, ungathered hem across the intermediate portion on the top edge of the front section of said garment, and sewing together 10 the edges of said scores and the side seams of said garment.

4. The method of making a yoke for a garment having a front and back section which comprises forming a hem at the upper 15 edge of the back section, providing a pair of scores extending downwardly from the upper edge of the front section parallel to

the side edges and in spaced relation thereto, forming hems adjacent each of said side edges by turning the material thereof downwardly over a strip of elastic material, sewing said elastic material under tension to each side of said turned-over material and simultaneously forming the marginal stitch of the hem adjacent to but spaced from said elastic material, forming a smooth, ungathered hem across the intermediate portion of the top edge of the front section of said garment, and sewing together the edges of 20 25 30 said scores and the side seams of said garment.

Signed by me, this 27th day of September, 1924.

EDWARD L. WILLIAMS.
